STEPHEN LUPES,

Inventor,

By Julian J. Wittal,
his Attorney.

UNITED STATES PATENT OFFICE

STEPHEN LUPES, OF NEW YORK, N. Y.

DEVICE FOR PERMANENT HAIR WAVES

Application filed January 24, 1929. Serial No. 334,688.

My present invention relates to the art of hair dressing and more particularly to the construction of a Marcel waving unit for forming permanent waves or curls in the hair.

5 In practice a Marcel or permanent waving "machine" is constituted by a set or number of individual separately handled waving elements, each connected by a suspension cord or wire with a metal ring or support, the 10 number of such units being about twenty, more or less.

The object of the invention is to provide an improved Marcel waving unit having means whereby the hair may be formed in well 15 defined, deep set, and gracefully curved permanent waves, eliminating sharp bends to obviate breaking or rupture of the hair strands following the heating and fixing operation of the device, thus providing at once a real permanent wave requiring no after treatment 20 such as finger curling and the like.

A feature of the construction is found in providing for each hair waving unit, an elongated body, preferably of rectangular cross 25 section, provided for the greater part of its length with a heating chamber separated by a cross wall from an exhaust chamber, but being in communication one with the other through an axial port, so that excess steam or 30 vapors may pass from heating chamber in the operation of the device.

A shallow jacket chamber surrounds the heating chamber and is adapted to carry and house an electric heating device or coil, the 35 exhaust and the jacket chambers having suitable covers to retain heat therein.

Another important feature of my invention resides in the construction and conformation of an improved hair carrying core, 40 constituted by a base plate having staggered recesses formed in its opposite sides and a projecting finger piece provided with a longitudinal slot or kerf in which a tuft of hair is first caught prior to being coiled or threaded around a series or number of staggered 45 posts formed at their ends with confining lugs, extending longitudinally of said base plate.

50 Centering springs are also provided on the base plate which bear against the inner walls

of the heating chamber when the core is in its operative position.

Various refinements may be made in the composition and configuration of the component elements going to make up the hair waving machine unit without departing from the scope of the invention and no limitation is intended by the phraseology of the following description except as indicated in the appended claim.

In the drawings similar reference characters are employed to designate corresponding parts throughout the several views in which:

Fig. 1 is a lady's head showing how a tuft of hair is prepared for waving in my improved unit and said view further shows another tuft as waved by my improvement.

Fig. 2 is a central longitudinal section of my improved permanent waving unit, showing a tuft of hair coiled or threaded on the posts of the wave setting core.

Fig. 3 is a bottom end view of the unit shown in Fig. 1 to more clearly disclose an asbestos cover for that end of the device.

Fig. 4 is a detail perspective view of the improved hair setting core employed.

Fig. 5 is a detail perspective of an asbestos cover for the open end of the heating chamber.

Referring now to the drawings in detail, I show at 10 my improved permanent waving unit which embodies an elongated body 11, provided with a heating chamber 12, an exhaust chamber 13 containing loose cotton 13^a, for impeding exhaust gases, and a jacket chamber 14 surrounding said heating chamber and separated therefrom by a side wall 15.

The heating and exhaust chambers 12 and 13 are separated by a cross wall 16, formed with an upwardly or outwardly directed tubular nipple 17, the bore 18 of which providing a passage through which excess steam, vapors or gases may escape from the heating chamber to the exhaust chamber and any moisture formed by condensation may be retained in the latter.

An electric heating coil 19 having appropriate conductor connections 20, may be confined in the jacket chamber which serves to

heat the hair receiving or heating chamber 12 through the heat conducting side wall 15.

The jacket chamber 14 may be tightly closed by an insulating cap 21 resting on a 5 packing 22 and held down by screws 23. The exhaust chamber 13 may also be closed by a cap 24 provided with interior grooves or passages 25 for the escape of excess gases as shown in Fig. 2 of the drawings.

10 The permanent waving unit 10 may be held in suspension by a cord or wire 26, attached to a screw-eye 27 and be manipulated in the hand by grasping the heat insulating cap 21.

15 An important part of my invention is present in a novel hair setting core, which embodies a base plate 28, a slotted finger extension 29, posts 30, formed with longitudinally extending confining lugs 31, at the tops 20 thereof, said posts being arranged in staggered relation at the opposite sides of base plate 28, and centrally arranged anchor posts 32 and 33 having confining shoulders 34 at their tops to confine the end portion of a tuft 25 of hair against outward movement.

In practice, a tuft of hair is selected and tied as shown at 40 in Fig. 1, after which it is coiled or threaded around or over the posts 30, 32, 33 of the setting core, a fixing solution 30 is then applied to the hair after which the whole may, if desired, be wrapped in asbestos or other cloth to which a fixing solution is applied before inserting into the heating chamber of the permanent waving device.

35 When the treatment is finished the core with its tuft of hair is removed from said chamber after which the hair is removed from the setting core, the result of such treatment being shown at 41 in Fig. 1 disclosing a beautifully curved permanent wave with uniform loops and no sharp bends obviating rupturing strains.

The mouth of the heating chamber 12 may be closed by a U-shaped asbestos cover 35 45 stiffened by a looped wire 36.

To properly center the inner end of the core 28, with respect to the heating chamber 12, I provide spring arms 37 which bear against the inner walls of said chamber when 50 said core is in its normal operative position.

What I claim as new, is:

A permanent waving unit of the class described including a hair setting core comprising a base plate formed with staggered side 55 posts having confining lugs at the tops thereof, centrally arranged anchor posts and oppositely directed spring arms for the purpose set forth.

Signed at New York, in the county of New 60 York, and State of New York, this 21st day of January, A. D. 1929.

STEPHEN LUPES.
